UNITED STATES PATENT OFFICE.

FRANK DORNBURGER AND FREDERICK REISSMANN, OF WESTPOINT,
NEW YORK.

SAFETY SIGNAL SYSTEM.

SPECIFICATION forming part of Letters Patent No. 786,736, dated April 4, 1905.

Application filed August 13, 1904. Serial No. 220,624.

To all whom it may concern:

Be it known that we, FRANK DORNBURGER and FREDERICK REISSMANN, citizens of the United States, residing at Westpoint, in the county of Orange and State of New York, have invented certain new and useful Improvements in Safety Signal Systems; and we do hereby declare the following to be a full, clear, and exact description of the invention, such as will enable others skilled in the art to which it appertains to make and use the same.

Our invention relates to an automatic safety signaling system; and it consists of certain novel features of construction and arrangement or combination of parts the preferred character or form whereof will be hereinafter clearly set forth, it being understood that we desire to comprehend in this application all substantial equivalents and substitutes fairly falling within the scope of our invention, inasmuch as various modifications and changes can be made in the construction without departing from the spirit or scope thereof.

The prime object of our invention, among others, is to render it practically impossible for a train to pass by a signal, as a semaphore set at danger-point, without the knowledge of the person or persons in the cab of the locomotive or motor.

Other objects and advantages will be hereinafter made clearly apparent, reference being had to the accompanying drawings, which are made a part of this application, and in which—

Figure 1 shows a side view of our invention as applied to use. Fig. 2 shows a view similar to that presented in Fig. 1, taken at right angles thereto. Fig. 3 shows a perspective view of the various parts of our invention separated from the locomotive, the position of the parts carried by the locomotive being indicated as in coöperation with a semaphore signal of the usual or any preferred construction.

In the detailed description hereinafter presented the various elements of our invention and coöoperating accessories will be referred

to by numerals, the same numeral applying to a similar part throughout the several views, and, referring to the numerals on the drawings, 1 designates a semaphore signaling post or support upon which the semaphore 2 is pivotally mounted in the usual or any preferred way and coöperatively disposed, in combination with the weighted lever 3 usually employed to normally hold the semaphore at danger-point or in a horizontal plane, a weight 4 being provided for this purpose, as is common. The semaphore-signal 2 is controlled in the usual manner, as by the rod or wire 4, extending downward in engagement with the bell-crank 5, mounted in any preferred way at the bottom of the post, a branch 6 of the bell-crank being connected with the rod or wire 6, leading to the watch-tower or other point where the attendant is located, all being accomplished substantially in the usual or any preferred manner. In carrying out our invention, however, we pivot the controlling bell-crank to the end of the shaft 7, which latter is mounted in suitable bearings 8, carried by the base member or block 9, anchored at the base of the post 1, as upon the end of a cross-tie 10, whereby the arm 11 may be rigidly secured to the inner end of said shaft. The arm 11 is secured upon the shaft 7 in such a way that when the signal 2 is disposed in a horizontal plane or at "danger" said arm will be disposed vertically, and therefore in position to be directly in the path of the bell-crank or other equivalent device carried by the locomotive or on some suitable part of the train, the office of said arm 11 being to operate said bell-crank or device in a manner hereinafter set forth. In the present instance we have shown a simple bell-crank having the branches 12 and 13 pivotally mounted upon the rod 14, carried by the bracket or plate 15, which latter by reason of the apertures 16 may be readily connected to some suitable part of the locomotive or other framework where it is to perform its office. The branch 13 is disposed directly upon the angular extension 17, carried by the lower end of the vertically-disposed rod 18, which latter is reciprocated

ingly mounted, as in apertures in the ends of the brackets 19 and 20, connected to any suitable part of the framework. The shaft or rod 18 is held normally upward by properly 5 mounting a compression or other form of spring between said brackets, as indicated by the numeral 21. The upper end of the shaft 18 is properly shaped to afford a support for the end of the controlling-lever or 10 crank-arm 22, said arm being provided with an adjustable weight 23 or equivalent device whereby said weight will be utilized to rotate or partially turn the shaft 24 when the support for the outer end of the arm 22 is removed, as is the case when the shaft 18 is 15 drawn downward as a result of the bell-crank arm 12 being brought into contact with the arm 11 incident to the passing of the train. We have provided means for utilizing the 20 rotation of the shaft 24 thus induced by the release of the arm 22 for the purpose of accomplishing three very desirable and important results—that is to say, the shaft 24 first 25 operates a valve 25 in the upper end of the pipe 26, which latter is an air-pipe communicating with the automatic brake system—and it is obvious that when the valve 25 is opened by a partial rotation of the shaft 24 the air will be allowed to escape, and thus 30 disturb the equilibrium in the air-brake system and cause an instantaneous application of the brakes. Secondly, we utilize the escape of the air by opening the valve 25 to blow a whistle 27, or other form of signal 35 might be used, as a pneumatically-operated bell, &c. A further desirable and important result we accomplish by the rotation or partial rotation of the controlling-shaft 24 is to operate the valve 28, whereby we entirely 40 cut off further flow of steam from the boiler through the pipe 29, leading to the throttle-valve, the result being substantially an automatically-controlled throttle for the locomotive.

45 It will be clearly obvious that instead of employing the shaft 24 to operate the throttle-valve, as would be required upon the locomotive, said shaft may be connected in any preferred way with any suitable switching device, as when an electric motor is employed, whereby the current will be entirely cut off.

50 It is thought from the foregoing description that the construction and combination of parts or elements constituting our invention will be made clearly apparent, though it may be stated that the operation is as follows: When the semaphore is occupying a horizontal position, or at "danger," it is obvious that the arm 11 will be disposed in a 55 vertical plane, and therefore directly in the path of the branch 12 of the bell-crank, the result being that the contact between the arm 11 and the bell-crank will instantly overcome the tension of the spring 21 and draw

the shaft 18 downward, leaving the weighted 65 arm 22 to partially rotate the shaft 24, the result being that the air in the brake system will be allowed to escape through the whistle, producing the warning and at the same time instantly setting the brakes, and, furthermore, at the same moment the steam in the pipe 29 or other source of energy will be entirely cut off, thus, in effect, automatically closing the throttle-valve and insuring that the train will be stopped in the shortest possible space. The object of the warning-whistle or equivalent device is to make the engineer aware that he is passing a signal set at "danger," as in the case of heavy fog, or to awaken him if it is fairly presumed he would 80 ever sleep at his post of duty. In case of disability of the engineer for any cause the warning-signal, as from the whistles 27, would communicate the situation at once to the fireman or other attendant and call for 85 his attention. It would therefore be practically impossible for the train to get past a signal set at "danger" and would therefore prevent the train from entering in upon a block of the trackway without full knowledge of the danger resulting from such trespassing.

Believing that the construction and manner of using our invention have thus been made clearly apparent, further reference to 95 the details is deemed unnecessary.

What we claim as new, and desire to secure by Letters Patent, is—

The herein-described safety signaling system comprising the combination of a semaphore or other signal 2; an arm 11 vertically disposed near the trackway and operatively connected with said signal whereby when the signal is at "danger" said arm will be vertically disposed and horizontally disposed 100 when the signal is moved out of danger; suitable valves; a common controlling-shaft 24 for said valves; suitable intermediate controlling devices between said shaft and the arm 11 whereby if said arm is disposed in the 105 pathway of said controlling devices the shaft 24 will be partially turned to simultaneously operate said valves, thereby cutting off the source of power leading to the throttle-valve or controller and also open the air-pipe leading to the braking system and suitable means as a whistle designed to utilize the escape of the air all combined substantially as specified and for the purpose set forth.

In testimony whereof we have signed our 110 names to this specification in the presence of two subscribing witnesses.

FRANK DORNBERGER,
FREDERICK REISSMANN.
